SEWING MACHINE WITH PULLER DRIVE

Richard H. Lukins, Chicago, Ill., assignor to Union
Special Machine Company, Chicago, Ill., a cor-
poration of Illinois

Application October 24, 1950, Serial No. 191,759

8 Claims. (Cl. 112—214)

1

This invention relates to improvements in puller mechanisms for sewing machines and has particular reference to a puller mechanism that is provided on a frame separate from the regular frame of the sewing machine but is mounted in fixed relation to the latter and is operatively connected with the latter to pull the work at a point beyond the point of stitch formation. This mechanism assists the regular work feeding devices of the sewing machine in advancing heavy work and renders the action of the feeding mechanism more reliable.

An object of the invention has been to provide a puller mechanism of the character indicated which is so combined with a regular flat bed sewing machine as to enable the latter to be operated at high speed, with uniform results, in the stitching of heavy fabrics.

Another object has been to provide a puller mechanism, having the foregoing capabilities, which may be so coupled with a regular flat bed sewing machine as to make possible a wide range of accurately controlled stitch lengths.

An important feature of the invention is the coupling of the puller mechanism with the regular sewing machine in such a way that the main driving means for the puller is effectively lubricated from a main lubricant reservoir within an enclosed portion of the sewing machine. For this purpose a special extension is provided from the enclosed lubricant reservoir of the sewing machine for supporting and enclosing an important portion of the operating connections between the sewing machine and puller mechanism. This enables thorough lubrication of such parts and permits constant operation of the puller mechanism at high speed.

Other objects, features and advantages of the invention will appear from a detailed description of an illustrative form of the same which will now be given in conjunction with the accompanying drawings, in which:

Fig. 1 is a view partly in elevation and partly in vertical section of a sewing machine embodied in the illustrative form of the invention;

Fig. 2 is a horizontal sectional view through the machine, taken substantially along the work supporting surface thereof, but with the cloth plate of the sewing machine removed to illustrate more clearly the parts beneath it;

Fig. 3 is a view largely in end elevation, as seen from the left in Fig. 2, but partly in vertical section and with certain cover plates broken away;

Fig. 4 is an enlarged detail view of a portion of

2

the mechanism, in vertical section along the broken line 4—4 of Fig. 2;

Fig. 5 is an enlarged, vertical sectional view of a portion of the mechanism, taken along the line 5—5 of Fig. 2;

Fig. 6 is a similarly enlarged, transverse, vertical sectional view through a portion of the machine, taken along the line 6—6 of Fig. 2; and

Fig. 7 is an enlarged, detail view of a part of the sewing machine mechanism, in vertical section along the line 7—7 of Fig. 2.

Referring now to the drawings, the machine comprises a supporting base plate 10 (Fig. 3) on which is mounted a sewing machine 11, of any suitable construction, and a puller mechanism 12, the latter being positioned in rear of the sewing machine and closely coupled therewith to assist in feeding the work. The illustrative sewing machine, forming part of the combination, comprises a bed 13 carrying at its top a cloth plate 13a providing a work supporting surface for the machine. At one end of the bed there extends upwardly a vertical standard 14 from which projects an overchanging arm 15 extending over the work supporting surface and terminating in a needle head 16. The standard 14 may, if desired, be formed integral with the bed of the machine, but for simplicity and convenience in manufacture of the frame, the standard is preferably made separate from the bed and secured thereto in any suitable manner, as by bolts or the like. The line of division between the bed and the standard is indicated at 14a in Fig. 1. This facilitates the machining of all of the top flat surfaces of the bed which are disposed in the same plane. The bed of the sewing machine is secured to the bed plate 10 in any suitable manner as by means of screws or bolts. Similarly, the frame of the puller mechanism 12 is secured to the bed plate 10 so

that the sewing machine and puller mechanism are firmly retained in a definite, predetermined relation to each other. As will be explained, the puller mechanism is formed with a work supporting surface which is at the same level as the top of the cloth plate 13a and is arranged to provide a smooth continuous surface in conjunction with the latter for the advancement of the work.

The illustrative sewing machine is of the flat bed type and may suitably be of the character disclosed in the Peterson et al. application, Serial No. 58,222, filed November 4, 1948, now Patent No. 2,598,426, dated May 27, 1952. It is provided with a main drive shaft 17 mounted in bearings in the bed of the machine and arranged longitudinally

55 of the bed. The shaft projects through the right

end wall of the bed and carries at its outer end a combined handwheel and pulley 18 through which the sewing machine and also the puller mechanism may be driven.

At a point beneath the vertical standard 14, the shaft 17 has a crank portion 19 which is connected by a pitman 20 with a lever 21 extending longitudinally of the overhanging arm and suitably pivoted therein on an axis 22. At its other end, which extends into the needle head, the lever is connected by a link 23 with a block 24 secured to a needle bar 25. The latter is mounted for vertical reciprocation in suitable bearings at the top and bottom of the needle head and is adapted to carry one or more needles 26 at its lower end. Three such needles are shown. Cooperating with the needles in stitch formation is a cover thread laying member 27 carried by a collar 28 secured to a sleeve 29. This sleeve is adapted to be oscillated within a bearing at the bottom of the needle head by means of a link 30 which is connected at one end to a ball pin extending from the sleeve and at its other end to the arm 31 secured to a rock shaft 32. The latter extends along the rear face of the overhanging arm, outside of the latter, but is enclosed at its two ends by suitable projections from the frame at the needle head and vertical standard, respectively. Adjacent the top of the vertical standard the shaft 32 carries an arm 33 which is preferably slotted to receive, adjustably, a ball pin which is connected by a pitman 34 with an eccentric 35 on the shaft 17. By varying the position of the ball pin in the slot of the arm 33 the stroke of the latter, and hence the extent of oscillation of the shaft, may be varied.

Cooperating with the needles, when they are beneath the work support as shown in Fig. 1, is a thread carrying looper 36 adapted to form a double locked stitch in conjunction with the needle thread or threads. Looper 36 is carried by an arm 37 rockably mounted at 38 on a sleeve 39. The latter is mounted on and secured to a rock shaft 40 for oscillation with the latter. The looper carrier arm 37 is adapted to be rocked about its pivot 38 to impart loop-seizing and shedding movements to the looper by means of a link 41 connected at its forward end with a ball pin carried by the arm 37 and at its opposite end with a ball pin carried by an arm 42. This arm is secured to a rock shaft 43 which, as best shown in Fig. 7, extends transversely of the bed of the machine and carries a yoke 44 at an intermediate point within the bed, just beneath the main shaft 17. Yoke 44 carries a ball pin which is connected by a pitman 45 with an eccentric 46 secured to the shaft 17 adjacent a coupling 47 which serves to connect the shaft 17 with an extension or further section 17a of the main shaft. Rotation of the shaft will, through the connections described, impart the loop seizing and shedding movements to the looper. Needle avoid movements are imparted to the looper by rocking of the shaft 40 by means of an eccentric 48 secured to shaft section 17a, this eccentric cooperating with a strap 49 of a pitman 50 which is connected with the lower end of an arm 51 clamped to the shaft 40 (Figs. 1 and 2).

The work feeding devices may include a pair of differentially operated four-motion feed dogs. The main feed dog may be secured to a member 52 and the auxiliary feed dog may be connected with a member 53 (Fig. 2). Member 52 forms part of a feed bar 54 pivotally mounted at the

upper end of a feed rocker 55 secured to or rockably mounted on a shaft 56. Feed rocker 55 is operated by a pin 57 projecting from the feed rocker parallel with, but spaced from the shaft 56 and connected by an arm 58 with the lower end of a link 59 (Fig. 3). Link 59 has a strap portion cooperating with an eccentric 60 which is adjustably mounted in a carrier 61 secured to the shaft section 17a to provide variable eccentricity of the eccentric. Rotation of the eccentric 60 will serve to rock the feed roller 55 about the axis of shaft 56 and thus impart feed and return movements to the feed bar 54 and its connected feed dog. The auxiliary feed dog carrier 53 is secured to a rod 62 mounted for reciprocation in suitable bearing lugs on the feed bar 54. A block 63 secured to the rod 62 is connected by a link 64 with a stud 65 (Fig. 3) adjustable to any desired position along an arcuate slot 66 in a member 67 carried by the feed rocker 55. By varying the position of the stud 65 in the slot 66 the rod 62 and hence the auxiliary feed dog may be given variable extents of movement in relation to the main feed dog. Lifting and lowering movements are imparted to both of the feed dogs by a suitable eccentric (not shown) secured to the shaft section 17a beneath the feed bar 54. Cooperating with the feed dogs in advancing the work is a presser foot 68 (Figs. 1 and 3) mounted at the lower end of a vertically movable presser bar 68a extending through the sleeve 29. It will be understood that the presser bar is spring urged downwardly to hold the work against the throat plate and the feed dogs.

Provision is made for automatic lubrication of the various moving parts of the machine. For this purpose, a lubricant reservoir 69 is provided in the bed of the sewing machine frame below the vertical standard 14. To increase the lubricant retaining capacity of the machine, a further reservoir 69a is provided beneath a portion of the work supporting surface of the sewing machine. In effect, the two reservoirs constitute but a single storage space for lubricant, the two being interconnected by one or more passages 70 in the wall which separates them. A wick 71 disposed in a vertical passage within the separating wall just beneath a bearing for the shaft 17 serves to deliver lubricant to the latter. Another wick 72 (Fig. 7) disposed in a vertical passage in a wall adjacent the coupling 47 serves to deliver lubricant to a bearing for the shaft section 17a. Lubricant from the reservoir 69a is delivered to the wick 72 through one or more openings 73. A part of the lubricant delivered through the opening 73 into the vertical passage in which wick 72 is located is also delivered to a transversely extending passage 74 for delivery to various points at the rear of the sewing machine frame. As best shown in Fig. 2, the passage 74 is intersected by a longitudinally extending passage 75 through which lubricant is delivered to transversely extending passages 76 and 77 in the base of the sewing machine. From the various passages indicated, lubricant is delivered to the several wear receiving parts of the mechanism through wick-filled tubes 78. The operating parts in the vertical standard and in the needle head are lubricated by spray created upon the engagement of the crank portion 19 of the shaft 17 with the lubricant in the reservoir 69. Some of this spray is carried directly to the bearings requiring lubrication, while some is directed to the desired

points by a wire 79 and a deflector 80 (Fig. 1). Another part of the lubricant carried by the spray is delivered along the lever 21 to the needle head for the lubrication of the parts therein. A lubricant mist is also created within the reservoir 69a and this is delivered to all of the bearing surfaces within this part of the enclosed portion of the frame.

Turning now to the puller mechanism, this may be a unit generally similar to that disclosed in the patent to Seymour No. 1,145,619, granted July 6, 1915. It comprises a base portion 81 having a plurality of feet 82 and arranged to be firmly secured by means of screws or the like to the main base 10. At the top of the base portion 81 there is carried a work supporting member 83 which presents a flat surface in the plane of the work support surface 13a of the sewing machine and, in effect, provides a relatively large, continuous surface across which the work may be readily advanced. A removable throat plate 83a may be provided in an opening in the member 83, this throat plate having a central slot or opening through which opposed rollers 84 and 85 of the puller mechanism may cooperate to grip and pull the work. These puller rollers may be of any suitable construction and may be formed of any appropriate material. They may, for example, be smooth surfaced rollers provided with a rubber covering or rim, or their outer surfaces may be metallic and formed with suitable ribs or corrugations to assist in feeding the work. The frame of the puller mechanism may follow the general contour of the sewing machine frame and include a vertically extending standard 86, in rear of the standard 14 of the sewing machine, and an overhanging arm which is parallel with the overhanging arm of the sewing machine and terminates in a head provided with bearing lugs 87 and 88. A vertically disposed bar 89, mounted for vertical movement in the lugs 87 and 88, carries a yoke 90 at its lower end which is arranged to straddle the top roller 85 and provide journals for a trunnion 90a projecting from the opposite ends of the roller. A collar 91 secured to the bar 89 is acted upon, in any suitable manner, by a spring (not shown) such as that disclosed in said Seymour patent. This serves to urge the top roller downwardly against the work or the lower roller. Suitable means are provided for lifting the top roller to facilitate introduction and removal of work; this may comprise a lever 92 pivoted on a stud 92a projecting from the overhanging arm of the puller mechanism frame. A spring 93 urges the lever into inactive position against a stop 94 on the frame. When it is desired to lift the top roller the lever 92 may be rocked to engage the under face of a stud 95 projecting from the collar 91. If desired, suitable connections from a knee press or foot treadle may be provided for so lifting the top roller whenever the presser bar of the sewing machine is lifted. An arrangement similar to that shown in said Seymour patent may be employed for this purpose. To prevent turning of the bar 89, a forked extension 96 of the collar 91 is adapted to straddle and slide along a fixed rod 97 carried by the head of the puller mechanism. The top roller 85 is not positively driven, but is rotated through frictional engagement with the work or with the lower roller.

Intermittent turning movements of the lower roller, adapted to impart a feeding action substantially equal to that of the feed dogs of the

sewing machine, are imparted by the mechanism best shown in Figs. 2, 4, 5 and 6. This includes an eccentric 98 secured to the main shaft 17 within the enclosed lubricant chamber 69a. A strap 99 cooperates with the eccentric and is provided with a rearwardly extending arm 100 which passes through an opening 101 provided in the rear wall of the bed of the sewing machine. At its opposite end the arm or pitman 100 is forked, as indicated at 102, to straddle a downwardly extending arm 103. This arm carries a pin 104 secured in the arm by a screw 105 and arranged for pivotal connection with the forked end 102 of the pitman. Arm 103 is clamped to a rock shaft 106 journaled in bearings 107 and 108 carried by bossed portions of a housing 109 secured to the rear face of the bed of the sewing machine. Screws 110 are provided to retain the housing and gasket 111 is provided between the housing and the rear wall of the sewing machine frame to provide an oil-tight seal around the opening through the wall. The housing 109 is provided with a hollow space aligned with the opening 101 in the sewing machine frame to form the indicated extension of the lubricant chamber 69a. This permits thorough lubrication of the connections at both ends of the pitman 100 and, at the same time, guards against the escape of lubricant from the chamber 69a. The bearings 107 and 108 may be made sufficiently tight to prevent the escape of any appreciable amount of lubricant along the rockshaft 106. Moreover, any special means desired may be provided to prevent the escape of lubricant at the outer ends of these bearings. A removable screw plug 107a (Fig. 5) may, for example, serve to seal the outer end of bearing 107 and, at the same time, provide access to the parts and a means of assembling and disassembling them.

Shaft 106 extends outwardly through one wall of the housing 109 and has secured to its outer end, adjacent the outer end of bearing 108, an arm 112. The latter may be secured to the shaft in any suitable way, as by copper welding. Screw threaded openings 113 are provided at different radial distances from the axis of shaft 106 along the arm 112. A screw threaded shank 114 of a ball pin 115 is adapted to be threaded into any one of the openings 113 depending upon the stitch length desired. Ball pin 115 is received by a strap 116 of a link 117, which has a strap 118 at its opposite end surrounding a ball pin 119. The latter is arranged to be secured in any desired position along an elongated slot 120 provided in an arm 121 which is clamped or otherwise secured to a rock shaft 122. By varying the position of the ball pin 119 along the slot 120 further variation may be provided in the extent of movement of the feed or puller rollers on each cycle of operation of the machine, to conform with any selected stitch length. It will be apparent that the combined adjustments at the two ends of the link 117 provide for a wide variation in stitch length. Thus, when the pin 115 is mounted in the top hole 113 of arm 112, the feed action of the rollers may be varied between 10 and 24 stitches per inch by appropriate adjustment of the pin 119 along the slot 120. When pin 115 is in the bottom hole 113 the stitch length may be varied between 3½ and 7 stitches per inch in the illustrated machine.

Rock shaft 122 is journaled in a bearing sleeve 123 mounted in the base of the puller mechanism frame and it extends at its opposite end into a

one-way clutch unit 124. The latter may suitably be of a construction similar to that disclosed in the patent to Seymour No. 1,292,099, granted January 21, 1919. As will be understood, the arrangement is such that turning of the arm 121 and shaft 122 in one direction i. e., anti-clockwise, Fig. 4, will be idle. Rotation of the driven shaft 122 in such anti-clockwise direction is prevented by the construction of the one-way clutch which includes a fixed sleeve 126 held against rotation 10 by clamping means 127. The driven shaft 125 of the clutch unit is journaled in a bearing 128 and carries the roller 84 at its outer end.

To close the top of the lubricant chamber 69a there is secured to the top of the bed of the sewing machine, over this chamber, a cover plate 129 (Figs. 4 and 6). This is secured by suitable screws such as indicated at 130 in Fig. 6. A gasket 131 (Fig. 4) is preferably provided between the cover plate and the top of the bed to effect a good seal. Cover plate 129 extends over the extension of the reservoir provided by the casing 109 as well as over the main part of the reservoir in the bed. It is disposed below the work support 13a and is spaced slightly from the latter, as shown in Fig. 6. To permit rocking of the arm 103 without interference, a slight spherical bulge 132 is provided in the cover plate over the clamping screw for the arm 103.

The operation of the machine is believed to be clear from the foregoing detailed description. Upon each revolution of the main shaft 17 of the sewing machine the various stitch-forming devices will be operated to form a stitch and the feed dogs will be operated to advance the work. Simultaneously, the lower puller roller will be rotated through an increment depending upon the stitch length desired and in coaction with the upper puller roller 85 will serve to pull the work so as to insure the proper action of the regular feed mechanism of the sewing machine. The arrangement is such, moreover, that the principal wear receiving parts of the puller driving mechanism are enclosed and effectively lubricated from the supply of lubricant in the sewing machine reservoir.

While an illustrative form of the invention has been disclosed in considerable detail, it will be understood that various modifications may be made in the construction and arrangement of the several parts without departing from the principles and scope of the invention.

What I claim is:

1. A sewing machine having a frame with a work supporting bed portion, a vertical standard and an overhanging arm, stitch forming and work feeding devices carried by said frame, means comprising a rotary shaft in said bed for driving said devices, walls forming an enclosed lubricant retaining chamber in said bed, said shaft extending through at least one wall of said chamber, a puller mechanism exterior of said chamber comprising a driven roller for pulling the work at a point beyond the point of stitch formation, and connections from said rotary shaft for driving said driven roller, said connections including an eccentric on said rotary shaft and a pitman driven by said eccentric and a portion of said connections extending through a wall of said chamber in oil tight relation thereto, said pitman being fully enclosed within said chamber.

2. A sewing machine having a frame with a work supporting bed portion, a vertical standard and an overhanging arm, stitch forming and

work feeding devices carried by said frame, means comprising a rotary shaft in said bed for driving said devices, walls forming an enclosed lubricant retaining chamber in said bed, said shaft extending through at least one wall of said chamber, a puller mechanism exterior of said chamber comprising a driven roller for pulling the work at a point beyond the point of stitch formation, and connections from said rotary shaft for driving said driven roller, said connections including an eccentric on said rotary shaft, a rock shaft extending from a point within said chamber to a point outwardly thereof, and a pitman wholly within said chamber for connecting said eccentric with said rock shaft for rocking the latter.

3. A sewing machine having a frame with a work supporting bed portion, a vertical standard and an overhanging arm, stitch forming and work feeding devices carried by said frame, means comprising a rotary shaft in said bed for driving said devices, walls forming an enclosed lubricant retaining chamber in said bed, said shaft extending through at least one wall of said chamber, a puller mechanism exterior of said chamber comprising a driven roller for pulling the work at a point beyond the point of stitch formation, and connections from said rotary shaft for driving said driven roller, said connections including an eccentric on said rotary shaft, a rock shaft extending from a point within said chamber to a point outwardly thereof, a pitman wholly within said chamber for connecting said eccentric with said rock shaft for rocking the latter, an arm connected with said rock shaft exterior of said chamber, a second rock shaft wholly outside of said chamber, an arm connected with said second rock shaft, and a link connecting said arms on said rock shafts, said link being variably connected with each of said arms for varying the effective lengths thereof.

4. A sewing machine having a frame with a work supporting bed portion, a vertical standard and an overhanging arm, stitch forming and work feeding devices carried by said frame, means comprising a rotary shaft in said bed for driving said devices, walls forming an enclosed lubricant retaining chamber in said bed, said shaft extending through at least one wall of said chamber, a puller mechanism having a separate frame connected in fixed relation to said first mentioned frame and comprising a driven roller for pulling the work at a point beyond the point of stitch formation, and connections from said rotary shaft for driving said driven roller, said connections comprising a rock shaft in each of said frames, means wholly enclosed in said chamber and arranged to receive lubricant therefrom for rocking the rock shaft in the first mentioned frame upon rotation of said rotary shaft, said rock shaft in the first mentioned frame extending through a wall of said chamber, and means exterior of said frame for interconnecting said rock shafts for operation in unison.

5. A sewing machine having a frame with a work supporting bed portion, a vertical standard and an overhanging arm, stitch forming and work feeding devices carried by said frame, means comprising a rotary shaft in said bed for driving said devices, walls forming an enclosed lubricant retaining chamber in said bed, said shaft extending through at least one wall of said chamber, a puller mechanism having a separate frame connected in fixed relation to said first mentioned frame and comprising a driven roller for pulling the work at a point beyond the point of

stitch formation, and connections from said rotary shaft for driving said driven roller, said connections comprising a rock shaft in each of said frames, means wholly enclosed in said chamber and arranged to receive lubricant therefrom for rocking the rock shaft in the first mentioned frame upon rotation of said rotary shaft, said rock shaft in the first mentioned frame extending through a wall of said chamber, and means exterior of said frame for interconnecting said rock shafts for operation in unison, said interconnecting means comprising an arm secured to each of said rock shafts and a connection between said arms adapted for variable attachment to each arm to vary the effective length thereof.

6. A sewing machine having a frame with a work supporting bed portion, a vertical standard and an overhanging arm, stitch forming and work feeding devices carried by said frame, means comprising a rotary shaft in said bed for driving said devices, walls forming an enclosed lubricant retaining chamber in said bed, said shaft extending through at least one wall of said chamber, means within said enclosed chamber for dispersing a lubricant mist throughout the same upon rotation of said shaft, a puller mechanism exterior of said chamber comprising a driven roller for pulling the work at a point beyond the point of stitch formation, and connections from said rotary shaft for driving said driven roller, said connections including an eccentric on said rotary shaft and a pitman driven by said eccentric, said pitman being fully enclosed within said chamber, said connections also including a part extending through a wall of said chamber in oil tight relation thereto.

7. A sewing machine having a frame with a work supporting bed portion, a vertical standard and an overhanging arm, stitch forming and work feeding devices carried by said frame, means comprising a rotary shaft in said bed for driving said devices, walls forming an enclosed lubricant retaining chamber in said bed, said shaft

extending through at least one wall of said chamber, a puller mechanism exterior of said chamber comprising a driven roller for pulling the work at a point beyond the point of stitch formation, connections from said rotary shaft for driving said driven roller, said connections including an eccentric on said rotary shaft and a pitman driven by said eccentric, said pitman being fully enclosed within said chamber, said connections also including a part extending through a wall of said chamber in oil tight relation thereto, and means for distributing lubricant from the supply in said chamber to driven parts inside and outside of said chamber.

15 8. A sewing machine having a frame with a work supporting bed portion, a vertical standard and an overhanging arm, stitch forming and work feeding devices carried by said frame, means comprising a rotary shaft in said bed for driving said devices, walls forming an enclosed lubricant retaining chamber in said bed, said shaft extending through at least one wall of said chamber, an auxiliary feed mechanism exterior of said chamber comprising a driven roller for advancing the work from the point of stitch formation, and connections from said rotary shaft for driving said driven roller, said connections including a rock shaft partially within said chamber and which extends through a wall of said chamber in oil tight relation thereto, means within said chamber inter-connecting said rotary shaft with said rock shaft for driving the latter, and means exterior of said chamber and connecting said rock shaft with said driven roller.
